UNITED STATES PATENT OFFICE.

CHARLEY DE FREESE, OF WESTPOINT, INDIANA.

CULTIVATOR.

No. 800,082.

Specification of Letters Patent.

Patented Sept. 19, 1905.

Application filed March 16, 1905. Serial No. 250,447.

To all whom it may concern:

Be it known that I, CHARLEY DE FREESE, a citizen of the United States, residing at Westpoint, in the county of Tippecanoe and State of Indiana, have invented certain new and useful Improvements in Cultivators; and I do declare the following to be a full, clear, and exact description of the invention, such as will enable others skilled in the art to which it appertains to make and use the same.

This invention relates to improvements in cultivators.

The object of the invention is to provide a cultivator having means whereby the axle thereof may be raised or lowered to adjust the plows or the cultivator-shovels to vary the depth at which the same are to work.

A further object is to provide an adjusting mechanism of this character which may be quickly and easily applied to the various forms of cultivators.

With these and other objects in view the invention consists of certain novel features of construction, combination, and arrangement of parts, as will be hereinafter described and claimed.

In the accompanying drawings, Figure 1 is a side elevation of a cultivator, showing the application of the invention, one wheel of the cultivator being removed. Fig. 2 is a rear elevation of the same with one wheel removed. Fig. 3 is a vertical sectional view through the device and a portion of the cultivator-axle. Fig. 4 is an enlarged side view 35 of the attachment removed from the cultivator. Fig. 5 is a horizontal sectional view of the same, taken on the line with the wheel-spindle; and Fig. 6 is an enlarged detail side view of the outer end of the wheel-spindle, 40 showing the construction of the adjustable tap for holding the wheels on the spindles.

Referring more particularly to the drawings, 1 denotes the cultivator, 2 denotes the axle, and 3 the supporting-wheels of the same. 45 These parts may be of the usual or any desired construction. Secured to the outer ends of the axle is a guide-frame 4, said frame consisting of a vertically-disposed plate 5, having formed on its outer side guideways 6. 50 On the upper end of the frame is arranged a segmental rack 7, said rack being also provided with a series of transversely-disposed apertures 8. On the inner side of the plate 5 is formed a laterally-projecting socket 9, 55 into which is adapted to be inserted the end of the axle 2, said axle having been provided

with a transversely-disposed bolt-hole 10, which when the same is inserted into the socket 9 is adapted to align with holes 12, formed in the walls of the socket, and through 60 said aligned holes is adapted to be inserted a bolt 13, whereby the frame 4 is secured to the end of the axle.

Slidably mounted in the guideway 6 on the plate 5 is a spindle-supporting plate 14, said 65 plate being provided with a laterally-projecting socket 15, in which is formed aligned apertures 16. Into the socket 15 is adapted to be inserted the inner end of the wheel-spindle 17, said spindle being provided adjacent 70 to its inner end with a transversely-disposed aperture 18. This aperture 18 is adapted to be brought into alignment with the apertures 16, and through said apertures is inserted a bolt 19, whereby said spindle is secured with 75 in the socket 15. In the socket 15 is formed an annular recess, which is adapted to receive the inner end of the wheel-hub, thus forming a sand band or guard to prevent the entrance 80 of dirt in the hub and axle. On the spindles 17 is journaled the supporting-wheel 3 of the cultivator.

Pivottally mounted on the upper end of the plate 5, adjacent to one edge of the same, is a hand-lever 20, said lever being provided 85 with a spring-projected pawl 21, which is adapted to engage the teeth of the segmental rack 7 to hold the lever in its adjusted position. On the lower end of the lever is arranged an offset arm 23, to the outer end of 90 which is pivotally connected the upper end of a link 23, the lower end of said link being pivotally connected to the spindle-plate 14, whereby when said lever 20 is swung in one direction or the other the spindle-plate, together with the spindle and cultivator-wheel, 95 will be raised or lowered, thus causing the cultivator blades or shovels to plow deep or shallow, as may be desired. In the apertures 8 of the segmental rack are adapted to be inserted cotter-pins or keys 23. Said pins or keys are adapted to limit the movement of the hand-lever in one direction or the other, thus forming a stop for said lever to enable the same to be repeatedly brought to the 100 same position without the necessity of carefully observing that the same has reached this point, this arrangement being used when it is desired to adjust the lever back and forth between certain positions.

On the outer end of the wheel-spindles 17 is arranged an adjustable wheel-securing tap

- 24, consisting of a sleeve or collar 25, on the inner end of which is formed an annular offset flange 26, adapted to project over the outer end of the wheel-hub. In the sleeve or 5 collar 25 are formed two series of spirally-disposed apertures 27, arranged on opposite sides of the sleeve. The apertures of one series are directly opposite or in alinement with corresponding apertures of the other series, said 10 corresponding apertures being adapted to be brought into alinement or coincidence with a transversely-disposed aperture formed through the end of the spindle, and through the alined apertures in said sleeve and spindle 15 is adapted to be inserted a pin 28, thereby holding said tap on the end of the axle. By forming the alined apertures in the sleeve 25 in a spiral manner the sleeve may be adjusted upon the end of the spindle by pushing the 20 same inwardly or outwardly and turning the tap until the apertures in the opposite side of the same are brought into alinement with the apertures in the end of the spindle, thus permitting the sleeve and tap to be secured 25 in its adjusted position. This adjustment of the tap permits the wear on the wheel or other parts to be compensated for.
- By providing a cultivator with an adjusting attachment of this character the supporting- 30 wheels may be quickly and easily raised or lowered to permit the cultivator blades or shovels on either or both sides of the cultivator to plow deep or shallow, as may be desired.
- 35 From the foregoing description, taken in connection with the accompanying drawings, the construction and operation of the inven-

tion will be readily understood without requiring a more extended explanation.

Various changes in the form, proportion, 40 and the minor details of construction may be resorted to without departing from the principle or sacrificing any of the advantages of this invention.

Having thus described my invention, what 45 I claim as new, and desire to secure by Letters Patent, is—

A cultivator of the class described having an arched axle having downwardly-turned and outwardly-extended crank ends, guide-frames having sockets on their inner sides 50 near their lower ends into which the outwardly-extended crank ends of the arched axle are secured, said guide-frames extending upwardly and being formed at their upper 55 ends with segment-racks, spindle-supporting plates mounted in said guide-frames for vertical movement and provided in their outer sides with sockets in which the inner ends of the spindles are secured, levers fulcrumed to 60 said segment-racks, links connecting said levers to said vertically-movable spindle-supporting plates, and means coacting with the segment-racks to lock said levers and spindle-supporting plates at any desired vertical ad- 65 justment.

In testimony whereof I have hereunto set my hand in presence of two subscribing witnesses.

CHARLEY DE FREESE.
